CLAIM

The ornamental design for a lacrosse head, as shown and described.

DESCRIPTION

FIG. 1 is a top, front, left side perspective view of a lacrosse head showing our new design;

FIG. 2 is an enlarged perspective view of the portion shown with the circle area identified as 2 in FIG. 1;

FIG. 3 is an enlarged, fragmentary, bottom, rear, left side perspective view of a portion of FIG. 1; and,

FIG. 4 is a top plan view of FIG. 1.

The dash-dot broken lines represent portions of the lacrosse head that form no part of the claimed design. The dot-dash broken lines represent boundaries of the claimed design and form no part of the claimed design.

1 Claim, 2 Drawing Sheets(56)
